Attorneys.

UNITED STATES PATENT OFFICE.

JAMES H. RAND, OF NORTH TONAWANDA, NEW YORK.

INDEX ELEMENT FOR CARD-INDEX SYSTEMS.

1,248,911.

Specification of Letters Patent. Patented Dec. 4, 1917.

Application filed October 9, 1916. Serial No. 124,505.

To all whom it may concern:

Be it known that I, JAMES H. RAND, a citizen of the United States, and resident of North Tonawanda, in the county of Niagara and State of New York, have invented new and useful Improvements in Index Elements for Card-Index Systems, of which the following is a specification.

This invention relates to card index systems of the kind wherein a series of cards or similar indexed elements are supported in a suitable frame one above another in overlapped spaced relation. In indexes of this character the cards are usually supported by a bar or strip to which the card is secured at one edge, said strip providing laterally extending projections at each side of the card removably engaging inwardly facing guide channels on the frame. This invention has to do particularly with the construction of the individual index elements for card systems of this general character, and consists in the novel features of construction hereinafter described and particularly pointed out in the claims.

In the accompanying drawings which illustrate certain embodiments of the invention,—

Figure 1 is a face view of an index card containing the invention;

Fig. 2 is a section on line 2—2 of Fig. 1;

Fig. 3 is a face view illustrating a modification; and

Fig. 4 is a section on line 4—4 of Fig. 3.

35 *a* represents the card body which has one margin bent to form an offset portion *b*, preferably in the form of a box-like structure and preferably substantially rectangular in cross section, as shown. The face of 40 the offset portion *b* stands in relief from the face of the card body. This offset portion or box-like structure *b* is preferably formed by bending the margin of the sheet material of which the card is formed first 45 forwardly, then upwardly, and then rearwardly, the bent margin terminating substantially in the plane of the body of the card, as shown in Fig. 2, and leaving the fourth or rear side of the box-like structure 50 open. This structure is substantially rec-

tangular in cross section and is formed integrally with the body of the card. It constitutes a supporting and stiffening element and may be extended at either side of the card beyond the edges of the card to form 55 supporting projections *b'*, *b'*, for engaging the inwardly facing guide channels of the index frame.

Instead of using the ends of the box-like structure *b* for engaging the frame channels, 60 a sheath *c* of transparent material such as sheet celluloid, slightly longer than the width of the card and having its ends inserted in the guide channels in the frame, may be used. Said sheath *c* preferably conforms in cross section to the shape of the box-like structure *b*, and the latter may be inserted or removed endwise through the sheath, in which it has a sliding fit. The lower wall *c'* of the sheath is bent rearwardly 65 and the upper part is bent rearwardly and downwardly as shown at *c*², whereby a longitudinal opening is provided between *c'* and *c*² through which the body *a* of the card projects. When the sheath is used and the 70 ends of the offset *b* are not relied upon to engage the guide channels of the frame, the lateral extensions *b'* may, if desired, be omitted; and also the rearwardly bent part 75 of the offset portion extending backward from the top edge of the offset face *b*, may be omitted. The face of the offset may be used if desired for receiving index characters or any desired inscription appropriate to the subject matter on the card body *a*. 80

I claim:

1. An index card having one margin bent to form an offset box-like structure substantially rectangular in cross section formed integrally with the card and standing in 90 relief from the face of the card.

2. An index card having one margin bent to form an offset box-like structure having three sides substantially rectangular in cross section, the fourth side being open, 95 formed integrally with the card and standing in relief from the face of the card.

3. An index card having one margin bent to form an offset box-like structure formed integrally with the card and standing in re- 100

lief from the face of the card and projecting laterally beyond each side edge of the card.

4. An index card having one margin bent to form an offset portion formed integrally with the card and standing in relief from the face of the card, and a sheath of transparent resilient material through which

said offset portion on the card may be inserted or removed endwise, said sheath having a longitudinal opening through which 10 the body of the card projects.

Signed by me at Boston, Massachusetts, this 22nd day of September, 1916.

JAMES H. RAND.
